UNITED STATES PATENT OFFICE.

JOSEPH DAIN, OF MOLINE, ILLINOIS, ASSIGNOR TO DAIN MANUFACTURING COMPANY OF IOWA, OF OTTUMWA, IOWA, A CORPORATION OF IOWA.

COUPLING FOR HAY-LOADERS.

1,107,763.

Specification of Letters Patent. Patented Aug. 18, 1914.

Application filed June 21, 1913. Serial No. 775,012.

To all whom it may concern:

Be it known that I, JOSEPH DAIN, a citizen of the United States, residing at Moline, in the county of Rock Island, in the State of Illinois, have invented certain new and useful Improvements in Couplings for Hay-Loaders, of which the following is a specification, reference being had to the accompanying drawings.

10 Hay loaders are connected to the rear ends of wagons in order that they may be drawn over the ground behind the wagons, such loaders acting to fill the wagons with hay gathered from the ground as the wagon and loader move. Ordinarily a loader is connected to a wagon by some coupling means that requires the driver or other attendant to crawl beneath the wagon or in between the wagon and loader and manipulate the coupling devices by hand to connect or disconnect the wagon and loader. Such a method of coupling and uncoupling is, at times, dangerous for if, while the man is so engaged, the team should start the man is liable to be injured, as will be well understood. Attempts have been made to provide coupling devices for connecting loaders to wagons whereby this danger could be avoided but they have not been wholly satisfactory.

30 It is the object of my invention to provide an improved coupling device of simple construction whereby the wagon to which a loader is to be connected can be backed up to a hay-loader and the two be automatically connected together, and which can be readily opened by the driver or attendant while on the loaded wagon so that the wagon is disconnected or freed from the loader as it is moved away by the team. This object I accomplish by the means illustrated in the drawings and hereinafter described. That which I believe to be new will be set forth in the claims.

45 In the drawings,—Figure 1 is a top or plan view of a portion of the front of a hay-loader and a portion of the rear of a hay-rack and showing the two devices connected by my improved coupling means; Fig. 2 is a top or plan view of my improved coupling; Fig. 3 is a vertical section through the coupling, the locking latch being shown in side elevation; and Fig. 4 is a vertical section at line 4—4 of Fig. 1 illustrating the friction

means employed for holding the draft-bars of the hay-loader in raised position.

In the several figures of the drawings corresponding parts are indicated by like reference numerals.

5 indicates the axle of a hay-loader, which hay-loader may be of any usual construction. 6—6 are the wheels of the loader journalized on said axle 5.

7—7 are two draft-bars each attached at one end to the loader-axle 5 a short distance from one of the wheels 6, these bars being clamped to the axle by means hereinafter described so that they will normally be held in a raised position. As shown, these bars 7 extend diagonally forward and their forward ends are connected together by a suitable bracket 8 preferably made as a casting, which bracket comprises, as best shown in Fig. 2, two inclined side pieces 9—9, to each of which the forward end of one of the arms 7 is bolted. The bracket 8 is of such width that the forward ends of the arms 7—7 are held a short distance apart, and from the base of the bracket and in the space over the separated ends of the arms 7—7, rise two parallel vertical walls 10—10 between which is located a latch 11 pivoted in place by a bolt 12 extending through the latch and the said walls 10—10. The front edge of the latch is sharply beveled or inclined downward and rearward as indicated at 13, so that it can be raised up automatically as hereinafter set forth.

14 indicates the hook portion of the latch and 15 indicates an upwardly extending arm at the forward end of the latch.

16—17 indicate upper and lower forwardly-projecting jaws at the front end of the bracket 8, such jaws diverging from each other, as clearly shown in Fig. 3, and thus presenting a wide mouth to receive a coupling link, ring or bail, which coupling member when received in such mouth will be properly directed by the inclined face of one or the other of the jaws 16—17 against the beveled or inclined face 13 of the latch 11. In the drawing, such coupling member is a bail 18 which is shown as suitably attached to a rear cross-bar 19 of a wagon-rack, but it of course may be attached otherwise to a wagon if desired. I deem it best to make the wagon member of the coupling in the form of a bail, as shown, and to give

to the central portion of the bail a bend to provide a small loop, as 20, in order that the loader will then be compelled to follow directly behind and substantially in the tracks 5 of the wagon much better when making a turn, as at the end of a field.

Referring again to the diagonal draft-bars 7-7, it is essential to the successful and automatic coupling together of the 10 wagon and loader that the said draft-bars be held raised to a proper height to have the bail 18 enter between the jaws 16-17, and to that end I provide means for so holding such bars. Such means comprise, in the 15 construction shown, a two-part clamp 21 embracing each of the hubs 25 at the inner ends of the draft-bars 7-7 through which hubs passes the axle 5. The two members of each clamp 21 are connected by means 20 such as a bolt 28 to the lower end of a standard or upright 29, which, as shown and described in my Patent, No. 901,074, dated October 13, 1908, acts as a support for the upper end of the hay-loader frame. 25 Through the lower ends of these clamp members passes a bolt 22 on which is mounted an expansible coiled spring 23 that at one end bears against one of the clamp members and at its other end bears against 30 a nut 24 screwed upon said rod. The frictional binding of the clamps 21 on the hubs 25 can be regulated by adjusting the nuts, as will be understood.

26 indicates a flexible connection, which 35 may be a rope, chain or cable, fastened to the latch-arm 15, such connection in the construction shown being secured to said arm through a link 27. Such connection is to be long enough to allow it to extend up 40 along one side of the loader where it can be reached by the attendant on the wagon, so that he can, by pulling on it, raise the latch to allow the disengagement of the bail 18 therefrom.

45 It will be understood that the latch is normally in its lowered position, as seen in Fig. 3, and when it is desired to connect the loader to a wagon, the wagon is backed up toward the front end of the loader and the 50 bail 18 extending out from the rear of the wagon will be caused to enter between the diverging jaws 16-17, and, by the inclined face of one of such jaws, will be directed against the rearwardly-inclined front edge 55 13 of the latch. As the pressure of the bail against such inclined edge continues the latch will be forced up sufficiently to permit the bail to pass the hook portion 14, and as soon as that takes place the latch drops by 60 gravity and the bail is effectively retained by the hook against withdrawal, thereby firmly coupling the loader and wagon together. When a sufficient load of hay has been piled upon the wagon by the loader the 65 uncoupling of the loader from the wagon is

readily accomplished by a pull by the attendant, who is on the load, on the connection 26 and the starting of the team. As soon as the wagon moves the pull on the connection is released by the attendant and 70 the latch drops, and will remain in position to again be coupled in the manner described to another wagon. It will be understood that the draft-bars 7-7 on the loader are held elevated by the friction means described 75 so that the coupling device at their forward ends is always presented at substantially the right height to receive the bail 18 on a wagon, the wide divergence of the inclined jaws 16-17 insuring the proper 80 entrance between them of the bail and compensating for any irregularity in the surface of the ground, or other cause, that might tend to present the coupling parts out of proper position relatively to each 85 other.

The arrangement of the draft-bars 7-7, in the diagonal manner shown makes, with the axle to which they are fastened, a triangular frame of great strength and one peculiarly well adapted to withstand the shocks that are necessarily incident to the backing up of a wagon to effect an automatic coupling of such wagon with the 90 loader.

95 What I claim as my invention and desire to secure by Letters Patent is,—

1. The combination with a vehicle, and a pair of draft-bars connected therewith and converging toward their forward ends, of means at the inner ends of said bars for engaging the axle of the vehicle, friction devices bearing upon said axle-engaging means and adapted to hold said draft-bars in operative position, and a coupling member attached to the forward ends of said draft-bars. 100

105 2. The combination with a vehicle, and a draft device connected therewith, of means carried by said draft device for engaging the axle of the vehicle, a friction device bearing upon said axle-engaging means and adapted to hold said draft device in operative position, and a coupling member attached to the forward part of said draft device. 110

115 3. The combination with a vehicle and a draft-device connected therewith, of means carried by said draft-device for engaging the axle of the vehicle, a two-part friction device bearing upon said axle-engaging 120 means and adapted to hold said draft-device in operative position, said friction device having two oppositely-located end portions spaced a distance apart, a spring for forcing said two ends toward each other to 125 hold the two parts of the friction device in engagement with said axle-engaging means, and a coupling member attached to the forward part of said draft device.

130 4. The combination with a vehicle and a

- 5 draft-device connected therewith, of means carried by said draft-device for engaging the axle of the vehicle, a two-part friction device bearing upon said axle-engaging means and adapted to hold said draft-device in operative position, said friction device having two oppositely-located ends spaced a distance apart, a bolt passing through said ends, a spring held on said bolt and bearing 10 against one of said ends to yieldingly hold the two parts of the friction device in engagement with said axle-engaging means, and a coupling member attached to the forward part of said draft-device.
- 15 5. The combination with a vehicle, and a draft device connected therewith, of means carried by said draft device for engaging the axle of the vehicle, a supporting standard for the vehicle frame, a friction device at 20 the lower end of said standard and bearing upon the said axle-engaging means to hold said draft device in operative position, and a coupling member attached to the forward end of said draft device.
- 25 6. The combination with a vehicle, and a draft device connected with the axle thereof, of friction means surrounding the axle for holding said draft device in operative position, and a coupling member attached to the forward part of said draft device.
- 30 7. The combination with a vehicle, and a draft device connected with the axle thereof, of a standard extending upward from the said axle, friction means connected with 35 said standard for holding said draft device in operative position, and a coupling member attached to the forward part of said draft device.
8. The combination with a vehicle, and a movable draft device connected with the axle thereof, of a supporting standard for the vehicle frame, friction means interposed between the draft device and the standard and secured to one of said parts and having frictional engagement with the other part, 40 said friction means being adapted to hold said draft device in operative position, and a coupling member at the forward part of said draft device.
9. The combination with a vehicle, and a draft device connected therewith, said draft device having at its inner end a hub that surrounds the axle of the vehicle, of a standard extending upward from such axle, means connected with said standard and 45 frictionally engaging said hub for holding said draft device in operative position, and a coupling member attached to the forward part of said draft device.
10. The combination with a vehicle, and a draft device connected therewith, said draft device having at its inner end a hub that surrounds the axle of the vehicle, of a standard extending upward from such axle, means connected with said standard and 50 frictionally engaging said hub for holding said draft device in operative position, a spring for holding said means in contact with said hub, and a coupling member attached to the forward part of said draft device.
